(57) **CLAIM**

The ornamental design for a power strip with lights as shown and described.

DESCRIPTION

FIG. 1 is a perspective view of a power strip with lights showing the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The drawings include a symbolic break in length of the article represented by wavy break lines. The appearance of any portion of the article between the break lines forms no part of the claimed design.

The broken lines in the drawings illustrate portions of the power strip with lights that form no part of the claimed design.

1 Claim, 8 Drawing Sheets
